RAILWAY TRACK CIRCUITS

Paul N. Martin, Penn Township, Allegheny County, Pa., assignor to Westinghouse Air Brake Company, a corporation of Pennsylvania

Original application July 18, 1944, Serial No. 545,519. Divided and this application April 30, 1946, Serial No. 665,944

3 Claims. (Cl. 246—34)

1

My invention relates to railway track circuits, and more particularly to track circuits using vacuum tubes for track relays.

The present application is a division of my copending application, Serial No. 545,519, filed July 18, 1944, for Vacuum Tube Circuits, now Patent Number 2,541,879, dated February 13, 1951.

When a vacuum tube and particularly a gas tube is used as a relay for a railway track circuit, the bias voltage used to control the conductive condition of the tube must be checked because the loss of a bias voltage might result in the tube being made conductive corresponding to the unoccupied condition of the track circuit when the section is occupied.

Accordingly, a feature of my invention is the provision of track circuit apparatus incorporating novel and improved means to check the bias voltage of a gas tube used as a track relay and to assure proper phase relationship for the voltages of the different tube circuits.

Other features, objects and advantages embodying my invention will appear as the specification progresses.

The foregoing features, objects and advantages embodying my invention are accomplished by a circuit arrangement which includes the shield grid or control electrode and the source of bias voltage in series in a bias circuit, and through which circuit power for the anode circuit is obtained. In this way a loss of the bias voltage or a broken element of the bias circuit results in a loss of power for the anode circuit and the tube cannot be fired in response to such failure. The control grid circuit includes means through which the phase relationship of the voltage applied to the control grid from the track rails can be preselected and thus proper phase relationship between the voltage of the control grid circuit and the voltages of the anode and shield grid circuits can be predetermined. In the present application the shield grid and the control grid are at times referred to as control electrodes because both of the grids serve to control the operating characteristics of the tube.

I shall describe three forms of track circuit apparatus embodying my invention, and shall then point out the novel features thereof in claims.

In the accompanying drawings, Fig. 1 is a diagrammatic view showing one form of railway track circuit embodying my invention when using a gas tube and an alternating current. Figs. 2 and 3 are diagrammatic views showing two dif-

2

ferent forms of railway track circuits embodying my invention when using gas tubes and coded direct current.

In each of the different views like reference characters are used to designate similar parts.

Referring to Fig. 1, the reference characters 1a and 1b designate the track rails of a stretch of railway track formed by the usual insulated rail joints with a track section D—E, and which section may be one section of a series of sections of a signal system. Section D—E is provided with a track circuit comprising a source of current connected across the rails at one end of the section and a track relay connected across the rails at the opposite end of the section. The immediate source of current for the track circuit of section D—E is a track transformer TE, a primary winding 6 of which is connected to an alternating current transmission line including line wires L1 and L2 connected to a generator, not shown. A secondary winding 7 of transformer TE is connected across the rails 1a and 1b a current limiting impedance 8 being preferably interposed in the connection.

The track relay for section D—E comprises a tube VI and associated circuits. Tube VI may take different forms, and it is disclosed as an indirectly heated gas tetrode having an anode 9, a cathode 10, a control grid 11 and a shield grid 12. Tube VI is provided with two terminals for the shield grid 12, each end of the grid 12 being connected to a terminal. Thus, a circuit connected to the two terminals of the shield grid includes the shield grid in series so that any break in the shield grid or its connections within the tube will interrupt the circuit. The filament of the tube VI is heated from a secondary winding 13 of a line transformer TL, a primary winding 14 of which transformer is connected across the transmission line.

Tube VI is provided with a control grid circuit receiving energy from the track rails through a track transformer TRD and a phase shifting impedance. Specifically, a primary winding 2 of transformer TRD is connected across the rails 1a and 1b through wires 67 and 68, a resistor 69 being preferably connected in multiple with winding 2. Secondary winding 4 of transformer TRD is included in the control grid circuit which extends from grid 11 through resistor 15 to the junction terminal of an adjustable inductance 16 and a resistor 5 connected in series across the outside terminals of winding 4, and from an intermediate terminal of winding 4 through a bias battery 71 and wire 70 to cathode 10. Thus the

current supplied to the rails through track transformer TE causes a voltage to be applied to the control grid 11 of tube V1, the phase of the voltage applied to the grid with respect to the phase of the voltage across the rails being predetermined through the inductance 16 and resistor 5. The resistor 69 is provided in order to limit the amount of phase shift with changes in ballast conditions, but such resistor may not be needed. Also, the bias battery 71 is provided to give a normal negative bias voltage, but such bias battery may not be required.

Shield grid or control electrode 12 is included in a biasing circuit that can be traced from the right-hand terminal of secondary winding 17 of line transformer TL through wire 18, primary winding 19 of a transformer TP, wire 20, one terminal of the shield grid 12, the shield grid 12, the other terminal of the grid and wire 21 to the left-hand terminal of winding 17. Wire 18 is connected to cathode 10 of the tube through wire 25, and thus the shield grid 12 is of a potential with respect to cathode 10 proportional to the voltage of secondary winding 17. An anode circuit for tube V1 extends from the top terminal of secondary winding 22 of transformer TP through a battery 72, resistor 23, winding of a relay CR, wire 24, plate 9 and intervening tube space to cathode 10 of tube V1 and wires 19 and 25 to the other terminal of winding 22. It is to be seen that secondary winding 17 of the line transformer TL not only supplies a bias voltage for the shield grid 12 with respect to cathode 10 but also supplies power through transformer TP to the anode circuit of the tube. Thus a loss of power at secondary winding 17 or a broken circuit element for the biasing circuit of shield grid 12 will result in a loss of power for the anode circuit of the tube.

Plus and minus signs have been placed on certain of the circuit elements of Fig. 1 to indicate the relative polarity of the parts during one half cycle of the voltage of the transmission line L1—L2, the relative polarity of these circuit parts being reversed from that indicated during the other half cycle of the voltage. During the half cycle, the voltage is that indicated by the plus and minus signs, the shield grid 12 is negative in potential with respect to cathode 10 and the anode 9 is positive in potential with respect to the cathode. The parts are so proportioned that the higher voltages of such half cycle applied to the anode are sufficient to fire the tube, except for the negative bias effected through the shield grid 12. It is to be pointed out that battery 72 is of a voltage insufficient to fire tube V1 and serves to aid in preselecting the portion of the cycle of the alternating voltage supplied through transformer TP the tube is conductive. The battery 72 may not be needed and may be omitted.

Normally, that is, when the track section D—E is unoccupied, the control grid 11 is driven positive in potential with respect to cathode 10 during the half cycle the anode 9 is positive and such positive bias voltage for the control grid 11 causes tube V1 to be fired and relay CR energized by the anode current. During the following half cycle of the voltage the anode 9 is negative with respect to the cathode 10 and the tube is deionized. On the next positive half cycle the tube is fired again so that relay CR is energized by impulses of the anode current and its armature is retained picked up as long as such impulses of current flow because of the slow release characteristic of the relay. It is to be observed that

the proper phase relationship of the voltage applied to the control grid 11 is preselected by the adjustment of the inductance 16 and resistor 5.

When the track section D—E is occupied, the control voltage impressed across control grid 11 and cathode 10 is shunted and the tube V1 remains non-conductive because of the bias voltage applied to the shield grid 12.

It is apparent that in Fig. 1 there is disclosed a track circuit using a gas tube as a track relay and through which tube a control relay CR is retained energized in response to the track section being unoccupied, and is deenergized when the section is occupied. Furthermore, a loss of power at winding 17 of the line transformer so that there is a loss of bias voltage for the shield grid 12 results in a loss of power for the anode circuit and the tube cannot be fired because of such failure. Also any broken circuit element for the shield grid circuit results in a loss of power for the anode circuit and the tube cannot be fired because of such a broken circuit element.

In Fig. 2, the rails 1a and 1b are formed with a track section D—E the same as in Fig. 1. Section D—E of Fig. 2 is provided with a track circuit, the source of power of which is a battery BE connected across the rails through a contact 180a of a code transmitter 180CT. Code transmitter 180CT may be of any one of the several constructions known to the art and it is sufficient for this application to point out that the coder 180CT is constructed to actuate a contact member 180b to recurrently engage contact 180a at a preselected code rate such as, for example, 180 times per minute, the arrangement being such that contact 180a is closed substantially one-half of each code period. It follows that the track circuit current for section D—E of Fig. 2 is a coded direct current of a preselected code rate.

The track relay means responsive to the coded direct current of the track circuit of Fig. 2 includes gas tube V1 and a code following relay CF together with associated circuits. The shield grid 12 of tube V1 is included in a biasing circuit extending from the positive terminal of a battery 26, through resistor 27, winding of a check relay CC, resistor 28, one terminal of shield grid 12 to its other terminal and wire 29 to the negative terminal of battery 26. Cathode 10 of tube V1 is connected through wire 30 to an intermediate terminal 31 of the resistor 28, and it is clear that shield grid 12 is made negative in potential with respect to cathode 10 by a voltage preselected by the position of the intermediate terminal 31. Also the check relay CC, which is included in series with the shield grid 12 is energized and picked up by the current flowing in this circuit, but that any broken connection or circuit element of the circuit results in the deenergizing of the check relay.

An anode circuit for the tube V1 of Fig. 2 can be traced from the positive terminal of battery 26, through resistor 27, front contact 32 of the check relay CC, winding of code following relay CF, wire 33, anode 9 and tube space to cathode 10 of the tube, wire 30 to intermediate terminal 31 of resistor 28 and thence through the shield grid circuit to the negative terminal of battery 26. Thus the anode 9 is made positive in potential with respect to the cathode 10 when the shield grid circuit is complete so that the check relay CC is energized. The parts are so proportioned that the voltage applied to the anode 9 is sufficient to fire the tube except for the nega-

tive bias voltage applied to the shield grid 12. Tube VI of Fig. 2 is provided with a condenser C1 and a resistor 34 together with a shunt path by which the condenser C1 is connected across the anode 9 and cathode 10 through a front contact 35 of the code following relay CF.

The control grid 11 is connected across the rails of the section D—E through a circuit including resistors 69 and 15 as will be readily understood by an inspection of Fig. 2.

Normally, that is, when the track section D—E of Fig. 2 is unoccupied, a control voltage is applied to the control grid 11 of tube VI each on period of the coded track circuit current due to the voltage drop across resistor 69, the control grid 11 being driven in the positive direction with respect to the cathode 10. This control voltage applied to the control grid 11 counteracts the negative bias voltage applied to shield grid 12 and the tube VI is fired causing the code following relay CF to be energized and picked up by the current flowing through the anode circuit. Prior to the picking up of the relay CF, the condenser C1 is charged through resistor 34 and the tube, the right-hand terminal of condenser C1 as viewed in Fig. 2 being the positive terminal. With relay CF picked up to close front contact 35 condenser C1 is connected directly across the anode and cathode of the tube VI to deionize the tube with the result relay CF is deenergized and released. The parts are so proportioned that the on period of the coded track circuit current is slightly less than the time required for the relay CF to be picked up and for condenser C1 to deionize the tube. Consequently, the relay CF is released and the tube is conditioned ready to be fired on the next on period of the track circuit current and such operation will be repeated as long as the track circuit is unoccupied. When the section D—E is occupied, the control voltage applied to the control grid 11 is shunted and tube VI remains non-conductive because of the negative bias voltage applied to the shield grid 12.

It is to be seen, therefore, that as long as section D—E is unoccupied, relay CF is operated at a rate corresponding to the code rate of the track circuit current and with relay CF operated to alternately close front contact 36 and back contact 37 current impulses of a code rate corresponding to the code rate of the track circuit current are applied to a decoding unit shown conventionally at 180DU to energize a control relay AA. Decoding unit 180DU may be of any one of the several constructions known to the art and is shown conventionally since its construction forms no part of my invention.

It is apparent that in Fig. 2 a loss of power at battery 26 so that there is a loss of bias voltage for the shield grid results in a loss of power for the anode circuit. Also a broken circuit element of the shield grid circuit results in deenergizing check relay CC to interrupt the anode circuit. Thus in Fig. 2 the tube VI cannot be fired due to a loss of bias voltage.

Referring to Fig. 3, the track rails 1a and 1b are formed with a track section D—E provided with a track circuit supplied with coded direct current of the polar impulse code type. Code transmitter 180CT of Fig. 3 is provided with a front contact 38 and a back contact 39 for governing a polar stick relay PS, the arrangement being such that when coder contact 38 is closed, a top winding of relay PS is energized to operate the armature of relay PS to the left to close polar contact 40 and when coder 75

contact 39 is closed, a lower winding of relay PS is supplied with current to operate the armature of that relay to the right to close polar contact 41. Thus when code transmitter 180CT operates to close its front contact 38 there is a brief period before polar relay PS is operated to open its right-hand polar contact 41 and when code transmitter 180CT is operated to close contact 39 there is a brief period before relay PS is operated to open its left-hand contact 40. During the brief period the coder is in position to close its contact 38 and the right-hand polar contact 41 of relay PS is closed, current is supplied to the track circuit from battery 42 current flowing through contact 43 of the code transmitter, wire 44, rail 1a, the track relay or the train shunt if the section is occupied, rail 1b, wire 45, and right-hand polar contact 41 to battery 42. This impulse of current I shall consider as being of positive polarity. During the brief interval the code transmitter is in a position to close contact 39 and the polar contact 40 of relay PS is closed an impulse of current is supplied from battery 47, the circuit extending through contact 46 of the code transmitter, wire 44, rail 1a, track relay or train shunt to rail 1b, wire 45, and polar contact 40 to battery 47. This code impulse of current I shall consider as being of negative polarity. It follows that for each code cycle of the code transmitter two code impulses are supplied to the track circuit, the impulses being of opposite polarity and each of relatively short duration.

The track relay means for Fig. 3 includes two gas tubes V2 and V3 of any suitable type such as an indirectly heated tetrode. Each tube V2 and V3 is provided with two terminals for the shield grid in the manner explained in connection with tube VI of Figs. 1 and 2. The tubes V2 and V3 have their filaments heated in any convenient manner.

Each tube V2 and V3 is provided with a combined shield grid and anode circuit, such circuit for tube V2 extending from the positive terminal of a battery 48, through resistor 59, anode 60 and tube space to cathode 53 of tube V2, a bias resistor 55, one terminal to the other of shield grid 52 of tube V3, wire 51, one terminal to the other of shield grid 50 of tube V2 and to battery 48. Similarly, the circuit for tube V3 extends from positive terminal of battery 48 through resistor 56, anode 61 and tube space to cathode 54 of tube V3, resistor 55, shield grid 52, wire 51 and shield grid 50 to the negative terminal of battery 48.

It is to be seen that with either tube conductive the current flows through resistor 55 and creates a voltage drop which serves as a negative bias voltage for the shield grids of the tubes. In other words, the anode current of either tube 60 serves to create a negative bias voltage for the other tube. If tube V2 is conductive the voltage drop across resistor 55 due to the anode current of tube V2 renders shield grid 52 of tube V3 negative in potential with respect to cathode 54, and if tube V3 is conductive the voltage drop created across resistor 55 due to the anode current of tube V3 renders shield grid 50 of tube V2 negative in potential with respect to cathode 53. This voltage drop across resistor 55 is also applied to the shield grid of the conductive tube but is ineffective to control that tube due to the characteristics of gas tubes. If tubes V2 and V3 are both conductive the voltage drop across resistor 55 is correspondingly increased but is ineffective under such conditions. The parts are so propor-

tioned that battery 48 is of a voltage sufficient to fire each tube were it not for the bias voltage applied to the shield grid through resistor 55. It is to be noted that with neither tube conductive there is no bias voltage applied to the shield grids. In practicing the invention the tubes V2 and V3 would be arranged for one or the other of the tubes to be initially conductive so that the shield grid of the other tube would be biased to maintain such other tube non-conductive until a control voltage is applied to such other tube in a manner to be explained shortly. As an alternative arrangement resistor 55 can be replaced by a battery.

A condenser C3 is connected across the anodes of the tubes V2 and V3 and serves to alternately deionize the tubes in the well-known manner when the tubes are alternately fired through control voltages alternately applied to the control grids of the tubes.

Resistor 69 is connected across the rails the same as in Fig. 2, and a right-hand portion of resistor 69 is included in a control grid circuit for tube V2 and a left-hand portion of resistor 69 is included in a control grid circuit for tube V3, as will be readily understood by an inspection of Fig. 3. Thus, when the section D—E is unoccupied each code impulse of the track circuit current creates a corresponding voltage drop across resistor 69, the polarity being according to the polarity of the track circuit impulse.

In describing the operation of the apparatus of Fig. 3, I shall assume that at the start the tube V3 is conductive and tube V2 is non-conductive, section D—E is unoccupied and the first code impulse of the track circuit current is one that causes the right-hand terminal of resistor 69 to be positive. Under such circumstances the control grid 62 of tube V2 is driven in the positive direction by the voltage drop across the right-hand portion of resistor 69. This control voltage opposes the bias voltage of shield grid 50 of tube V2 and the parts are so proportioned that such control voltage permits tube V2 to be fired. With both tubes V2 and V3 conductive, the charge of condenser C3 is applied across the tubes in series and the polarity of the charge is such that tube V3 is deionized. Subsequent to the deionizing of the tube V3 the condenser C3 discharges through the circuit through tube V2, resistor 55, the shield grids 52 and 50 and connecting wire 51 and battery 48 and resistor 56. Subsequent to the discharge of condenser C3 it is recharged due to the voltage drop across resistor 59 caused by the conductive condition of tube V2, the right-hand terminal of condenser C3 being the positive terminal. The next code impulse of the track circuit current is of reverse polarity, and the voltage drop across resistor 69 causes its left-hand terminal to be positive and a control voltage is applied to control grid 64 of tube V3 to drive grid 64 in the positive direction in opposition to the bias of the shield grid 52. Such control voltage applied to tube V3 causes that tube to be fired. With both tubes conductive, the charge of condenser C3 is applied across the tubes and the polarity of the charge is such that tube V2 is deionized. Condenser C3 is now recharged with its left-hand terminal the positive terminal. The next impulse of track circuit current is one that causes the right-hand terminal of resistor 69 to be positive and tube V2 is fired in the manner explained hereinbefore. The charge of condenser C3 now is applied to the tubes to deionize tube

V3, and subsequent to the deionizing of tube V3 the condenser C3 is recharged with its right-hand terminal positive.

It is to be seen from the foregoing that the impulses of the track circuit current alternately fire the tubes V2 and V3 and an electromotive force alternating in polarity at a rate corresponding to the code rate of the impulses of the track circuit current appears across the outside terminals of resistors 56 and 59. This electromotive force appearing across resistors 56 and 59 is applied to a decoding unit 180DU tuned to effectively energize a control relay AA when the polarity of the electromotive force alternates at a frequency corresponding to the code rate of the track circuit current.

When the section D—E is occupied, the control voltage created across resistor 69 is shunted and the alternate operation of the tubes V2 and V3 ceases with one or the other of the tubes left conductive.

It is apparent that in Fig. 3 a loss of power that will cause a loss of the bias voltage applied to the shield grids 50 and 52 will also cause a loss of power to the anode circuit. Also, any broken connection in the combined shield grid and anode circuit of either tube V2 or V3 will open such anode circuit and the tubes cannot be fired.

It is to be understood that my invention is not limited to a shield grid as the control electrode of a tube to be provided with two terminals and included in series with a bias voltage source and other tube electrodes can be used.

Although I have herein shown and described but three forms of railway track circuits embodying my invention, it is understood that various changes and modifications may be made therein within the scope of the appended claims without departing from the spirit and scope of my invention.

Having thus described my invention, what I claim is:

1. In a track circuit the track rails of which are supplied with code impulses of direct current alternate in polarity, a track relay means comprising; a first and a second gas tube each of which has an anode, a cathode, a control grid and a shield grid; each said tube having two terminals which are connected one to each end of the shield grid of the same tube to include the shield grid in series with its two terminals, a combined shield grid and anode circuit for each of said tubes and each of which circuits includes in series, a battery, the anode to cathode tube space of the respective tube, a bias resistor and the two shield grids; said bias resistor and shield grids being common to the two shield grid-anode circuits, each said shield grid circuit being disposed to provide a preselected shield grid bias voltage for the tube due to the voltage drop across said resistor, said battery of a voltage to fire the tubes but normally ineffective due to said bias voltage of the shield grid of each tube and which bias voltages are checked by said series connections of the shield grids and their terminals in the shield grid-anode circuits, circuit means connected across the control grid and cathodes of said first and second tubes, said circuit means including a resistor which is connected across said track circuit to receive said current impulses and which resistor is provided with terminals that are connected to said control grids and cathodes and poled to drive the control grid of said first tube positive in response

to current impulses of one polarity when they are applied to said circuit means and to drive the control grid of the second tube positive in response to current impulses of the other polarity when they are applied to said circuit means, means including a condenser connected across the anodes of said tubes and two other resistors one interposed in each of said shield grid-anode circuits to deionize the tubes whereby said tubes are alternately fired in response to current impulses of alternate polarity applied to said circuit means, and means connected to said shield grid-anode circuits of said tubes energized in response to such alternate firing of the tubes.

2. In a track circuit the track rails of which are supplied with impulses of current alternate in polarity, a track relay means comprising, a first and a second gas tube each of which has an anode, a cathode and a first and a second control electrode; each of said tubes having two terminals connected to the opposite ends of the second electrode of the tube, a source of direct voltage, a resistor; an anode-cathode circuit for each of said tubes and each of which circuits includes in series the positive terminal of said source, the anode to cathode tube space of the respective tube, said resistor, the second control electrode and its two terminals of each of the two tubes and the negative terminal of said source; said source of direct voltage being sufficient to fire each tube, said resistor being of a value sufficient for its voltage drop due to the conduction current of either tube to negatively bias the second control electrode of each tube sufficiently to render the source of direct voltage ineffective to initially fire the tube, said negative bias being checked by the series arrangement of the anode-cathode circuits to include each second control electrode and its two terminals, another resistor connected across said track circuit to receive energy for current to flow therethrough due to said impulses of current, control circuit means to connect one outside terminal and a mid terminal of said another resistor across the first control electrode and cathode of said first tube and to connect the other outside terminal and the mid terminal of said another resistor across the first control electrode and cathode of said second tube, and deionizing circuit means including a condenser connected across the anodes of the two tubes and two other resistors one interposed in each of the said anode-cathode circuits adjacent the anode of the respective tube.

3. In a track circuit the combination comprising, a track section, means including a source of current connected across the rails of said section and operative to supply current impulses alternate in polarity; a track relay means including a first and a second gas tube each of

which has an anode, a cathode and a first and a second grid; each said tube is provided with two terminals which are connected to opposite ends of the first grid of the tube, a source of power voltage, a source of bias voltage; an anode-cathode circuit for each tube and each of which circuits includes in series said power source of voltage, the anode to cathode tube space of the respective tube, said source of bias voltage and the first grid and its two terminals of the respective tube; said source of power voltage being poled to render the anode of each tube positive in potential with respect to the cathode of the tube and being of a voltage sufficient to fire the tube, said bias voltage source being poled to render the first grid of each tube negative in potential with respect to the cathode of the tube and being of a voltage sufficient to render said source of power voltage in effective to fire the tube, each said tube being provided with a check as to its nonconductive condition due to said two terminals connected to the opposite ends of the first grid of the tube and due to said series arrangement of its anode-cathode circuit, circuit means including a resistor connected across the rails of said section and having one outside terminal and a mid terminal connected across the second grid and cathode of said first tube and its other outside terminal and the mid terminal connected across the second grid and cathode of said second tube, the voltages applied to said second grids due to said track circuit current flowing in said resistor being effective to alternately overcome said bias voltages of said first grids and enable said power source of voltage to alternately fire the tubes, means including a condenser connected across the anodes of the tubes to alternately deionize said tubes, and control means having an element common to said anode-cathode circuits energized by the conduction currents of the tubes.
